UNITED STATES PATENT OFFICE.

THOMAS A. PLATT, OF BROOKLYN, NEW YORK.

IMPROVEMENT IN SELF-ADJUSTING EYE-SHADES.

Specification forming part of Letters Patent No. **195,045**, dated September 11, 1877; application filed January 29, 1877.

To all whom it may concern:

Be it known that I, THOMAS A. PLATT, of Brooklyn, in the county of Kings and State of New York, have invented a new and useful Improvement in Self-Adjusting Eye-Shades, of which the following is a specification:

The figure is a perspective view of one of my improved eye-shades.

The object of this invention is to furnish an improved eye-shade, which shall be so constructed that it will adjust itself to the shape and size of the head, and may be worn without causing pain or annoyance to the wearer.

The invention consists in an improved eye-shade formed by the combination of the two springs with each other and with the shade, as hereinafter fully described.

A represents the shade, which is crescent-shaped, and may be made of any desired size. The shade A is made of pasteboard, covered with cloth of a green, blue, or other desired color. To the concave edge of the shade A is attached a light metal spring, B, to rest

against and fit upon the forehead of the wearer. To the ends of the spring B are secured, by rivets or other suitable means, the ends of a similar metal spring, C, to pass over the head of the wearer, and thus keep the shade A in place.

The springs B C should be covered with cloth to keep them from hurting the head, and from being rusted by perspiration.

The spring C may be adjusted at any desired angle with the spring B.

Having thus described my invention, I claim as new and desire to secure by Letters Patent—

A self-adjusting eye-shade, consisting of the shade A, provided with the spring B, made fast to the upper edge thereof, and the spring C, pivoted to the ends of spring B, as shown and described.

THOS. A. PLATT.
